Des. 114,320

TOOL FOR ADJUSTING IGNITION CIRCUIT BREAKERS

Filed July 20, 1938

FIG. 1.

FIG. 2.

INVENTOR
HARRY EISNER

BY
Theodore S. Simonton
ATTORNEY

UNITED STATES PATENT OFFICE

114,320

DESIGN FOR A TOOL FOR ADJUSTING IGNITION CIRCUIT BREAKERS

Harry Eisner, Union Springs, N. Y.

Application July 20, 1938, Serial No. 78,602

Term of patent 3½ years

To whom it may concern:

Be it known that I, Harry Eisner, a citizen of the United States of America, residing in the city of Union Springs, county of Cayuga, and State of New York, have invented a new, original, and ornamental Design for a Tool for Adjusting Ignition Circuit Breakers, of which the following is a specification, reference being had to the accompanying drawing, forming part thereof.

Figure 1 is a perspective view of a tool accord-

ing to my design with the various parts in closed relationship; and

Figure 2 is a perspective view showing the tool partially opened with three main parts at varying angles to one another.

I claim:

The ornamental design for a tool for adjusting ignition circuit breakers, substantially as shown.

HARRY EISNER.
